UNITED STATES PATENT OFFICE.

THOMAS CHRISTIAN THOMSEN, OF COPENHAGEN, DENMARK, ASSIGNOR TO MESSRS.
KOEFOED, HAUBERG, MARSTRAND & HELWEG, AKTIESELSKABET TITAN, OF COPENHAGEN, DENMARK.

CENTRIFUGAL SEPARATOR.

Application filed July 9, 1926, Serial No. 121,403, and in Denmark March 8, 1926.

Centrifuges are often employed for cleaning various liquids and for removing substances suspended in them. Thus centrifuges are frequently employed in chemical 5 cleaning establishments for cleaning the used benzine from particles of cloth, dust, dirt or the like solid substances suspended in the benzine.

These centrifuges, however, have the disadvantage that the solid substances which are readily separated, collect at certain points in the drum of the centrifuge whereby the working capacity of the centrifuge is greatly reduced. It is the object of the 15 present invention to ensure the separation of the solid particles in all parts of the drum, so that these particles separated will collect in an even layer of somewhat the same thickness along the inside of the wall 20 of the drum, wherefrom such layer is easily removed when the drum inset is provided with a bottom outside ridge having the shape of a scraper and passing along the inside of the drum when the inset is raised.

25 The invention is shown in the accompanying drawing, in which Fig. 1 is a vertical longitudinal section, partly broken away, along the line I—I in Fig. 2.

Fig. 2 shows the centrifuge drum with inset but after the upper part has been removed.

30 Numeral 1 indicates the central guide tube of the centrifuge bowl and is adapted to seat on the shaft of a rotor (not shown). The bowl or drum of the centrifuge is preferably formed of a frusto-conical bottom 2, a cylindrical outer wall 3 and a frusto-conical upper wall 4, the walls 3 and 4 being 35 removably secured together by the clamping nut 5.

40 Centrally disposed in the drum or bowl is an inset 6 adapted to rotate therewith and having a central opening 12 in the top thereof. The bottom of the inset 6 is continued outward as at 7 and abuts the wall 3 of the drum, thus serving to scrape the inside surface of wall 3 when the inset 6 is raised.

45 Inset 6 is provided, in the present embodiment of the invention, with pairs of imperforate walls 8, each pair of walls forming a cell 10. In the drawings I have shown four pairs of radial walls, but it will be understood that this number of pairs of walls may be varied and that the walls need

not be radial. Communication between the 55 top of the bowl and the space between the cells is afforded by opening 12 in the top of the inset and openings 14 in the vertical wall of the inset 6.

Each cell is provided with an opening 9 60 in the rear wall thereof, which opening is preferably located at the bottom of the wall to be as remote as possible from the openings 14 in the inset 6. Each opening 9, therefore, forms a means of communication 65 between the respective cell 10 and the space or chamber 11 immediately behind the cell.

The liquid to be purified is introduced into the bowl through the opening 12, and as the bowl is rapidly revolving, the body 70 of liquid will assume the form of an approximately vertical cylinder covering the inside of the wall 3 of the bowl. The substances suspended in the liquid will be deposited over the entire inner surface of said 75 wall 3. As more and more impure liquid is introduced into the bowl, the thickness of the wall of the liquid cylinder covering the inner surface of the wall 3 will be increased 80 until the addition of more impure liquid 85 will force out through the opening 13 in the top of each cell some of the purified liquid.

It will thus be seen that the liquid, after it has been purified in the spaces or chamber 11, must travel through the openings 9 85 and up through cells 10 and out of openings 13.

In this manner, the complete removal of the substances suspended in the liquid is ensured, and the suspended material deposited evenly over the entire inner surface 90 of wall 3 whence it may be easily removed.

It is evident that many changes may be made in the specific construction described, and the invention is therefore to be limited 95 only by the scope of the following claims.

Having now described my invention, what I claim as new and desire to secure by Letters Patent is:—

1. A centrifuge for removing suspended substances from liquids, comprising, a bowl having an opening centrally disposed in the top thereof, a plurality of pairs of walls extending outward from the center of the bowl, each pair of walls forming a cell, and an opening in the rear wall of each cell communicating with the space between the cells. 100

2. A centrifuge for removing suspended

substances from liquids comprising, a bowl having an opening centrally disposed in the top thereof, an inset in the center of the bowl, a plurality of pairs of walls extending outward from the inset, each pair of walls forming a cell, and an opening in the rear wall of each cell communicating with the space between the cells.

3. A centrifuge for removing suspended substances from liquids comprising, a bowl having an opening centrally disposed in the top thereof, an inset in the center of the bowl, a plurality of pairs of walls extend-

ing outward from the inset, each pair of walls forming a cell communicating through an opening in its top with the opening in the bowl top, openings in the inset forming means of communication between the bowl top opening and the space between the cells, and an opening in that portion of the rear wall of each cell remote from said inset openings and communicating with the space between the cells. 15 20

In testimony whereof I affix my signature.

THOMAS CHRISTIAN THOMSEN.
